UNITED STATES PATENT OFFICE.

LORING COES, OF WORCESTER, MASSACHUSETTS, ASSIGNOR TO THE COES
WRENCH COMPANY, OF SAME PLACE.

DESIGN FOR A WRENCH-HANDLE.

SPECIFICATION forming part of Design No. 32,656, dated May 15, 1900.

Application filed April 16, 1900. Serial No. 13,144. Term of patent 14 years.

To all whom it may concern:

Be it known that I, LORING COES, a citizen of the United States, residing at Worcester, in the county of Worcester and State of Massachusetts, have invented and produced a new and original Design for a Wrench-Handle, of which the following is a specification, reference being had to the accompanying drawing, forming a part thereof.

10 The drawing in perspective shows a wrench-handle illustrating my design.

The leading feature of my design for a wrench-handle consists of a barrel-like head having an offset lip and two elongated legs 15 connected between their free ends and the head by a transverse band.

Referring to the drawing, the barrel-like head a has at one end a laterally-offset lip a' and at its opposite ends two elongated legs a^2 ,

connected between their free ends and the head by a transverse band or tie a^3 . The convex surface of the head and the sides of the lip a' merge gracefully into each other, and the outer edges of the legs are convexed slightly in the direction of their length.

Having fully described my design, what I claim, and desire to secure by Letters Patent, is—

The design for a wrench-handle, substantially as herein shown and described.

In testimony whereof I have signed my name to this specification in the presence of two subscribing witnesses.

LORING COES.
